UNITED STATES PATENT OFFICE.

GEORGE H. PATTEN, OF CHATTANOOGA, TENNESSEE, ASSIGNOR TO PATTEN MANUFACTURING COMPANY, OF CHATTANOOGA, TENNESSEE, A CORPORATION OF TENNESSEE.

TIRE-PUMP.

1,244,365.

Specification of Letters Patent. Patented Oct. 23, 1917.

Application filed May 19, 1917. Serial No. 169,719.

To all whom it may concern:

Be it known that I, GEORGE H. PATTEN, a citizen of the United States, residing at Chattanooga, in the county of Hamilton and 5 State of Tennessee, have invented new and useful Improvements in Tire-Pumps, of which the following is a specification.

This invention relates to tire pumps adapted for use with automobile and other 10 tires; and the primary object of the same is to provide means in connection with the pump barrel to cause the axis of the latter and the plunger to follow the natural oscillation of the body of the operator as the 15 plunger is reciprocated during the pumping action and whereby a more positive and forceful stroke may be given to the plunger and reduction of wear on the bearing cap or bearing device for the plunger rod or 20 stem is reduced to a minimum and at the same time the operation of the pump is effected with less tiresome exertion upon the operator.

With these and other objects and advantages in view the invention consists in the construction and arrangement of the several parts which will be more fully hereinafter described and claimed.

In the drawing:

30 Figure 1 is a side elevation of a tire pump embodying the features of the invention.

Fig. 2 is an enlarged elevation of the lower portion of the pump looking at the latter in a plane at right angles to that 35 shown by Fig. 1.

Fig. 3 is a detail side elevation of a portion of the tire pump showing a modified construction.

The numeral 5 designates the barrel of an 40 ordinary air pump having a bearing cap 6 applied to the upper end and a support 7 secured to the lower end. The pump barrel will have the usual air inlet and other pumping attachments, and within the same is 45 mounted a plunger 8 to which is attached a rod or stem 9 which extends through the bearing cap 6 and is provided with an upper handle or grip 10. The base support 7 embodies the features of the improvement and consists 50 of a semicircular pressure member 11 having a fulcrum rib 12 extending longitudinally of the center of the bottom portion thereof, the flat side of the semicircular pressure member forming the main bottom portion of the 55 support or base and the curved part of the

latter stands uppermost for engagement by the foot of the operator. The pressure member 11 extends equally in opposite directions relatively to the center or axis of the pump barrel 5 and the fulcrum rib 12 is reduced 60 toward its lower edge 13, the said edge being rounded, as clearly shown by Fig. 2. Preferably the opposite ends of the fulcrum rib 12 are cut away at a downward and inward angle of inclination, as at 14, to give 65 a clearance at the opposite ends of the rib and provide for a more sensitive rocking action thereof without resistance of corners or angles that would become worn if the said rib extended out in planes at right 70 angles to the under flat side of the pressure member 11.

In the form of the device shown by Fig. 3 the barrel 5 and the remaining parts of the pump are similar to those shown by Figs. 1 and 2, but the support or base differs in structure in that it is provided with an upwardly extending yoke or stirrup member 15 connected to the opposite ends of the pressure member 11 which is slightly shorter 80 than that shown by Fig. 1 and has the same form of fulcrum rib 12 extending longitudinally of the center thereof.

The operation of the improved pump in either of its forms is very simple, and when 85 it is desired to use the pump in inflating a tire the rib 12 is disposed upon a support which may be a road or street surface or other means upon which an automobile having the tire needing inflation is resting. The support or base is also held adjacent to the tire to be inflated and the operator places either foot upon the upper curved surface of the pressure member 11 at one side of the barrel 5 and then proceeds to reciprocate 90 the rod or stem 9 to actuate the plunger 8 to pump the air into the tire. During the pumping action the barrel 5 together with the plunger 8 and the rod or stem 9 will follow the natural oscillation of the body 95 as the plunger and its rod are vertically reciprocated, and by this means a direct and positive force may be applied to the plunger and rod or stem with less tiring effect upon the operator and with more favorable results in inflating tires. As hereinbefore noted, wear on the parts of the pump and particularly the plunger and the bearing cap is reduced to a minimum in view 100 of the fact that there is no irregular bind- 105 110

ing set up between the several parts during the actuation of the pump and particularly between the rod or stem 9 and the cap 6. Moreover, bending or distortion of the rod 5 or stem 9 is less liable to occur in view of the fact that the barrel 5 will always assume the proper angle relatively to the line of draft or the pushing force exerted on the plunger 8 and rod or stem 9.

10 Another very material advantage of the improved pump is that the usual leather washer of the piston 8 will be prevented from becoming irregularly worn as in the ordinary pump structures embodying rigid barrels or bodies and wherein one portion of the washer is worn to a greater extent than the remaining portion by reason of the irregular pull exerted on the plunger or piston and rod therefor. By means of the improved pump hereinbefore disclosed the pulling and pushing stress on the plunger or piston will be uniform or central with regard to the latter and therefore the washer will be regularly worn and will not be subject to the disadvantages incident to imposing greater wear on portions thereof than on other portions of the same.

It will be understood that the parts of the improved tire pump will be made of suitable metal to render the same strong and durable and it is obvious that the upper curved surface of the pressure member will give an easy movement of the support or base of the pump relatively to the foot of the operator during the oscillation of the pump as an entirety.

In the operation of the modified construction as shown by Fig. 3 the foot of the operator is inserted through the stirrup 15 and 40 rests on the pressure member 11, the upper

surface of the pressure member being semi-circular and the stirrup large enough to permit free movement of the base support relatively to the operator's foot.

What is claimed as new is:

1. A tire pump comprising a barrel having a plunger and rod or stem, and a base support embodying a pressure member with an upper curved surface and a lower rib extending longitudinally thereof at the center to form a fulcrum means for permitting the axis of the pump barrel and plunger to follow the natural oscillation of the body of the operator as the plunger is actuated. 45

2. A tire pump of the class specified comprising a barrel having a plunger and rod or stem, and a base support having a centrally disposed fulcrum rib to permit an oscillation of the pump during its operation. 50

3. A tire pump of the class specified comprising a barrel with a plunger and rod or stem coöperating therewith, and a base support embodying a semicircular pressure member having a rib extending longitudinally of the center of the bottom portion 60 thereof to serve as the fulcrum means. 65

4. A tire pump of the class specified comprising a pump barrel having a plunger and rod or stem coöperating therewith, and a base support embodying a stirrup having a pressure member with a lower longitudinally disposed fulcrum rib at the center thereof. 70

In testimony whereof I have hereunto set my hand in presence of two subscribing witnesses. 75
